UNITED STATES PATENT OFFICE.

ELMER S. SMITH, OF NEWARK, NEW JERSEY.

CARBURETER.

1,196,890.

Specification of Letters Patent.

Patented Sept. 5, 1916.

Application filed September 2, 1915. Serial No. 48,652.

To all whom it may concern:

Be it known that I, ELMER S. SMITH, a citizen of the United States, residing at Newark, in the county of Essex and State of New Jersey, have invented certain new and useful Improvements in Carbureters; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in carbureters; and, this invention has reference, more particularly, to a novel construction of carbureter adapted to be connected with the main gasolene supply tank, wherever the same may be located, relative to the hydro-carbon engine which the carbureter is to serve.

The invention has for its principal object to provide a simple and novel construction 25 of carbureter adapted to be combined with the main gasolene supply tank in a novel and efficient manner, either within the tank or exteriorly thereof; and, the invention has for its further object to provide a novel 30 construction of air-delivery means, combined with a novel carbureting mechanism and a gaseous fuel-delivery means, all so combined and related as to assure a proper performance of the carbureting function, 35 even at a considerable distance from the hydro-carbon engine which is to be served, such, for example, as when the main gaseous supply tank and the novel carbureter mechanism combined therewith are located at 40 the rear end of an automobile, and thus farthest removed from the engine.

Another object of the present invention is to provide a novel construction of carbureter adapted to automatically supply an exceedingly rich priming charge of gaseous fuel to the engine served thereby, when cranking or starting the said engine.

Other objects of the present invention not at this time more particularly enumerated, 50 will be clearly understood from the following detailed description of this invention.

The invention consists, primarily therefore, in the novel carbureter hereinafter set forth; and, the invention consists, furthermore, in the novel arrangements and combinations of the several devices and parts,

as well as in the details of the construction of the said parts, all of which will be more fully described in detail in the following specification, and then finally embodied in the clauses of the claim which are appended to and which form an essential part of said specification.

The invention is clearly illustrated in the accompanying drawings, in which:—

Figure 1 is a detail longitudinal cross section of the main gasolene supply tank having combined therewith the novel construction of carbureter showing one embodiment of the principles of the present invention, 70 said carbureter being also shown in longitudinal cross section; and Fig. 2 is a detail horizontal section of said novel construction of carbureter, said section being taken on line 2—2 in said Fig. 1, looking in a downward direction. Fig. 3 is a detail longitudinal cross section of a main gasolene supply tank having combined therewith, and exteriorly connected thereto, a slightly modified construction of my novel carbureter, the latter embodying, however, the general principles of the present invention.

Similar characters of reference are employed in all of the said above described views, to indicate corresponding parts.

Referring now to Figs. 1 and 2 of the accompanying drawings, the reference-character 1 indicates a main gasolene supply tank, one wall of which, preferably the upper wall, is provided with an internally screw-threaded opening 2, which is normally closed by a screw-cap 3. The said opening 2 is large enough to permit the insertion therethrough of my novel carbureter, presently to be described, so that the same may be located within the said tank 1, and submerged in the supply of gasolene stored in said tank 1. The said novel construction of carbureter comprises a casing 4 of any desirable shape, the same being provided, in a suitable location, with a valve-body 5 having a gasolene-admission valve-opening 6, in which is arranged a suitable shut-off valve-member 7. Said valve-opening 6 provides a means of communication between the interior of said casing 4 and the interior of the main supply tank 1, so that the gasolene contained in said tank 1 may enter the control-chamber 8 provided by the interior of said casing 4. 110 The operation of said shut-off valve-member 7 is automatically controlled by means of

a float 9 arranged within the control-chamber 8. Said float 9 is connected with one end of a lever 10 which is pivoted upon a fulcrum-lug 11 formed in connection with 5 said valve-body 5, and the opposite end of said lever 10 is provided with a bifurcated portion or fork 12 which enters an annular groove 13 formed in the head 14 of said valve-member 7. When a desired amount of 10 gasoline enters through the valve-opening 6, so that the proper level thereof is reached in the control-chamber 8, the float 9 rises, thus oscillating the lever 10 to depress the valve-member 7, and thereby shut off the valve-opening 6 against the further admission of 15 gasoline, until the carbureting operation withdraws gasoline from the control-chamber 8, thus lowering the level of gasoline, whereupon an opposite movement or lower- 20 ing of the float 9 oscillates the lever 10 to lift the valve-member 7, and thereby re-opens the valve-opening 6 to the further admission of gasoline from the main supply-tank, these operations continuing automatically as the float 9 rises and falls.

The upper end of the casing 4 is closed by a suitable cover-member 15, which screws upon, or is otherwise suitably secured in closing relation to said casing 4. Said cover-member 15 is provided with a centrally located and downwardly extending tubular member 16 which terminates at its upper end in an internally screw-threaded receiving socket 17. Said tubular member 16 terminates at its lower end, within the control-chamber 8, and short of the bottom thereof. The lower end of said tubular member 16 is provided with a closure 18 in which is fixed a centrally located and upwardly extending 35 jet-member 19, the lower end of which is open to communication with the interior of said control-chamber 8. Screwed into said receiving socket 17 is an air-tube or conduit 20 which extends upwardly through said 40 main supply tank 1 and passes through the screw-cap 3 thereof, the same having a screw-connection with said screw-cap 3, whereby the same is held in a fixed position, and also in supporting relation to said casing 45 and its cover-member 15. Communicating with the outwardly projecting end or head 21 of said air-tube or conduit 20 is an extension 22 which may lead to any convenient point so as to communicate, if desired, with 50 a controllable air-admission valve to be operated by the driver of an automobile, when the present invention is applied to automobile use. Said outwardly projecting end or head 21 of said air-tube 20 is provided with 55 an internally screw-threaded opening 23, through which passes downwardly into and through said air-tube 20, a gas-conveying tube 24, the same having a screw-threaded connection with said opening 23, whereby 60 the same is secured in proper fixed and rela-

tive position within said air-tube. Said gas-conveying tube 24 extends downwardly into said tubular member 16, and terminates short of the bottom thereof. Said gas-conveying tube 24 is of smaller diameter than 70 the air-tube 20, so that an air-passage 25 is provided between the same and the walls of said air-tube. The passage 26 of the gas-conveying tube provides a path through which the gas formed by the admixture of 75 gasoline and air exits from the carburetor. The outwardly projecting or head-end 27 of said gas tube 24 is provided with a communicating extension 28 which may lead to a gas-admission and control valve-mechanism 80 connected with the manifold of the internal combustion engine to be served by the carburetor.

The upper end of said jet-member 19 projects upwardly into the lower end of said 85 gas-tube 24, and is provided at its termination with an inverse cone-shaped valve-seat 29. Coöoperating with this valve-seat 29 is a needle-valve member 30, adapted, when manipulated, to increase or decrease the area 90 of the jet-outlet. The stem 31 of said needle valve member 30 extends upwardly through said gas-tube 24 and is provided at its upper end with a screw-threaded shank 32, which has a threaded connection with a 95 bushing 33, the latter in turn having a threaded connection with the said head-end 27 of the gas-tube 24 for fixing the same, and for closing the opening in said head-end 27 giving admission of the needle-valve 100 member and its stem to the gas-tube 24. The outwardly projecting end of said shank 32 is provided with a knurled fingerpiece 34 for turning said shank to raise and lower the said needle-valve member and its stem 105 as desired, and for the purposes above indicated. Said jet-member 19 is provided with a minute outlet opening or secondary jet-discharge 35 which is located in its body in such a position as to discharge into the 110 lower end of said tubular member 16 which forms a part of the air-passage 25 beneath the mouth of the gas-tube 24. The upper end of the jet-member 19, forming its main and normal discharge point, is maintained 115 in the plane of the normal level of the gasoline in the control chamber 8, or slightly above such plane. While I have described a certain location for said minute outlet opening or secondary jet-discharge 35, I do 120 not limit myself to its location in such a position, since all that is necessary or essential as to its location is that it be placed in a plane somewhere below the normal level of the gasoline in said control chamber 8, and in position to discharge the gasoline from 125 said jet-member so that the same will flood the lower end of said air-passage 25 and the entrance to said gas-tube 24, for the purposes to be hereinafter disclosed.

If desired, the casing 4 may be formed at its bottom portion with a depending boss 36 which acts as a stop or spacing member whereby the bottom of said casing 4 cannot be lowered into contact with the bottom of the reservoir 1 so as to obstruct the flow of gasoline to the admission-valve opening 6.

When the carbureter, constructed as hereinabove described, is connected in communication with the cylinders of an internal combustion engine which it is to serve, the operation of the pistons in the cylinders of said engine causes a suction-like action to be set up in said gas-tube 24, the effect of which is to cause atmospheric air to rush into said air-tube 20. Descending the passage 25 and entering the lower end of the gas-tube 24, the air rushes past the jet-member 19, the needle-valve member 30 being raised from the seat 29, and sucks a spray of gasoline from the discharge end of said jet-member, which becomes intermixed and incorporated with the air and forms therewith the combustible gas or fuel. The gas or fuel, thus produced, passes upwardly through the passage 26 of the gas-tube 24, and thence through the extension 28 to the cylinders of the engine. The gas, thus delivered, may be passed through any suitable construction of throttling or controlling mechanism located at the manifold of the engine, or in any other convenient place in the gas delivery line.

It will thus be apparent, that the present invention provides a very simple and effective means for generating combustible fuel at a distance from the engine, if desired, and carrying the same to a throttling means within easy controlling reach of the operator of the engine. For example, in automobile use, the main supply tank and novel carbureter-device may be carried at the rear of the vehicle, while the carbureter thus positioned will supply the gas to a throttling means connected with the engine-manifold and within easy reach of the operator at the forward end of the vehicle. When the engine stands idle, the gasoline from the control chamber 8 and rising in said jet-member 19, will flow out of the minute outlet-opening or secondary jet-discharge 35, and will rise in said air-passage 25 and gas-passage 26 until it reaches the level of the gasoline in the control chamber 8. This raw charge of gasoline is termed a priming charge, since when the engine is cranked or started and suction is established in the gas-tube 24, this raw charge of gasoline is carried to the engine-cylinders, taking up and intermixing with it, as it goes, some air, but in any event passing into the engine-cylinders as a very rich and highly explosive primary charge. As the raw gasoline passes through the gas-tube 24 and its extension 28, it coats the inner sides thereof with a

film of gasoline, which minimizes the tendency of the following ordinary gas charges to condense or loose strength by adherence of gasoline-particles to the walls. When the engine is running continuously, the gasoline is taken from the main discharge point at the upper end of the jet-member 19, as that provides the point of least resistance to its quick exit from the jet-member under the influence of the passing stream of air, and consequently the secondary jet-discharge 35 is practically inoperative as an exit under ordinary conditions of operation, but operates only, or at least most effectively, when suction ceases in the gas-tube 24, and, furthermore, by reason of its minute size and the presence of the gasoline in the jet-member there is no tendency of the air to enter said jet-member therethrough.

Referring now to Fig. 3 of the accompanying drawings, I have illustrated therein a slightly modified construction of carbureter which embodies, however, the same novel principles of construction and operation which comprise the subject-matter of the present invention. In this construction, I have slightly modified the carbureter-casing and the jet-member, and have arranged the former for exterior association with a main gasoline supply tank 1, instead of an interior association therewith. The reference-character 37 indicates a casing of any desired shape, and 38 indicates a cover-member therefor. The cover-member 38 is provided in a suitable location with a valve-body 39 having at its upper end an internally screw-threaded receiving socket 40 into which screws a feed-pipe 41, the opposite end of which is secured to the main gasoline supply tank 1, in any suitable manner, and in communication therewith. Said valve-body 39 depends into the interior 42 of the casing 37, and is provided at its lower end with a valve-opening 43. Arranged in said valve-body is a gravity shut-off valve-member 44, having a stem 45 of smaller diameter than the valve-opening which extends downwardly through the latter into the interior 42 of the casing 37. The operation of said shut-off valve-member 44 is automatically controlled by means of a float-member 46 arranged in the interior or control-chamber 42 of the casing 37. Said float 46 is connected with one end of a lever 47 which is pivoted to a fulcrum-lug 48 formed in connection with said valve-body 39, and the opposite end of said lever has a lift-portion 49, which at the proper times is carried into lifting and consequently into valve-opening relation with the free end of said valve-stem 45. The rise and fall of the float operates the above-described valve-mechanism to admit and shut off gasoline from the main supply tank 1 whereby the normal level of the gasoline in the control chamber 42 is main-

tained. Integrally formed with said cover-member 38 is a vertically extending tubular member 50. Said tubular member 50 extends downwardly through the control-chamber 42, and is provided at its closed lower end with an externally threaded portion 51, which projects through an opening in the bottom of said casing 37. A nut 52, with a suitable gasket, screwed upon said portion 51 serves to draw the cover-member 38 and casing 37 together into sealed relation. Said tubular member 50 is provided at its lower end, within the casing 37, with a plurality of holes or openings 53 through which the gasolene in the control-chamber 42 flows into the lower end or basin-chamber 54 of said tubular member. Said tubular member 50 is further provided with a lateral closing partition or wall 55 above said openings 53, which prevents gasolene from entering the interior of the upper end of said tubular member which forms an air-passage 56. The reference-character 57 indicates an adjustable jet-member which extends upwardly through the bottom of said tubular member 50, having a screw-connection with the bottom of said tubular member 50, whereby said jet-member may be adjusted bodily and vertically by turning the same, the lower exterior end of said jet-member having a knurled fingerpiece 58 for operating the same. Said jet-member extends upwardly through said basin-chamber 54, and passes through said partition or wall 55. Communicating with the outwardly projecting or head-end 59 of said tubular member 50 is an air-pipe or conduit 60, which may be led to any convenient point, so as to connect, if desired, with a controllable air-admission-valve to be operated by the driver of an automobile, when the present invention is applied for automobile use. Said outwardly projecting or head-end 59 of said tubular member 50 is provided with an internally threaded opening 61, through which passes downwardly into and through the air-passage 56 a gas-conveying tube 62, the same having a threaded connection with said opening 61, whereby the same is secured in proper fixed position within said air-passage 56. Said gas-conveying tube 62 terminates at its lower end, short of the bottom of said air-passage 56 formed by the partition or wall 55. The passage 63 of said gas-tube provides a path through which the gas formed by the admixture of gasolene and air exits from the carburetor. The outwardly projecting or head end 64 of said gas-tube is provided with a communicating gas-pipe or conduit 65, which may be led to a gas-admission and control valve-mechanism connected with the manifold of the internal combustion engine to be served by the carburetor. The upper end of said jet-member 57 projects upwardly into the lower end of said gas-tube 62, and is provided at its termination with an inverse cone-shaped valve-seat 66. Coöoperating with this valve-seat is a needle valve-member 67, the stem 68, of which extends upwardly through said gas-passage 63, and is provided at its upper end with a screw-threaded shank 69 which has a threaded connection with the head-end of said gas-tube 62. The exterior end of said shank 69 has a knurled fingerpiece 70 for manipulating said valve-stem and valve-member. Said jet-member 57 is provided with a tubular passage 71 terminating at its upper end in the valve-seat 66 and closed at its lower end. Communicating with the lower end of the passage 71 is an intake port or opening 72, through which the gasolene flows from said basin-chamber 54 into the passage 71. Said jet-member 57 is provided with a minute outlet-opening or secondary jet-discharge 73, which is located so as to discharge gasolene, at the proper times, into said tubular member 50 above the partition or wall 55.

The operation of the modified construction of carburetor just described is substantially the same, and is governed by the same principles, and produces the same advantageous results as already described hereinabove in connection with the first-described construction of carburetor, so that a further description of such operations is rendered unnecessary. It is to be further noted, that in both constructions of carburetors, the tubular member 16 of one, and the tubular member 50 of the other, is provided with an opening 74 which admits air into the float-chamber of the carburetors so that a proper flow of gasolene to the respective jet-members thereof is assured.

I am aware that some changes may be made in the general arrangements and combinations of the various devices and parts as well as in the details of the construction of the said parts, without departing from the scope of the present invention as set forth in the foregoing specification, and as defined in the clauses of the claim which are appended thereto. Hence, I do not limit my invention to the exact arrangements and combinations of the said devices and parts as described in the said specification, nor do I confine myself to the exact details of the construction of the said parts, as illustrated in the accompanying drawings.

I claim:

1. The combination with a main gasolene supply tank, of an inclosed control-chamber having a float-controlled gasolene-admission valve-mechanism, air-conveying means in communication with the atmosphere entering said control chamber, said air-conveying means being closed at its bottom end, a gas-discharge means extending telescopically into said air-conveying means and ter-

minating short of the bottom of said air-conveying means so as to communicate at that point therewith, a jet-member communicating at its lower end with said control chamber and extending through the bottom of said air-conveying means upwardly into the lower end of said gas-discharge means, and means connected with the outer end of said gas-discharge means for conveying gas to an internal combustion engine.

2. The combination with a main gasolene supply tank, of an inclosed control-chamber having a float-controlled gasolene-admission valve-mechanism, air-conveying means in communication with the atmosphere entering said control-chamber, said air-conveying means being closed at its bottom end, a gas-discharge means extending telescopically into said air-conveying means and terminating short of the bottom of said air-conveying means so as to communicate at that point therewith, a jet-member communicating at its lower end with said control-chamber and extending through the bottom of said air-conveying means upwardly into the lower end of said gas-discharge means, and means connected with the outer end of said gas-discharge means for conveying gas to an internal combustion engine, said jet-member having a secondary minute discharge-opening located in a plane below the normal level of gasolene in said control-chamber and discharging into the lower end of said air-conveying means.

3. The combination with a main gasolene supply tank, of a tubular member providing an air-passage closed at its bottom end entering said tank and its contents, said tubu-

lar member being open at its outer end to atmospheric air, a second tubular member open at its bottom end and providing a gas-discharge passage, said second tubular member being of smaller diameter than said first tubular member and being arranged to extend downwardly through said first tubular member but terminating short of the lower closed end of the latter, the outer end of said second tubular member having a gas-conveying pipe connected therewith and adapted to be led to an internal combustion engine, a jet-member extending through the closed lower end of said first tubular member so that its upper discharge end enters the lower open end of said second tubular member, and means connected with the lower end of said first tubular member for regulating and controlling the flow of gasolene into said jet-member, comprising a control-chamber surrounding the lower end of said first tubular member, and a float-controlled gasolene-admission valve-mechanism for admitting gasolene from said main supply tank into said control-chamber, said jet-member having a secondary minute discharge opening located in a plane below the normal level of gasolene in said control-chamber and discharging into the lower closed end of said first tubular member.

In testimony, that I claim the invention set forth above I have hereunto set my hand this 28th day of August, 1915.

ELMER S. SMITH.
